UNITED STATES PATENT OFFICE.

JAMES W. ARTHUR, OF WARREN, OHIO.

METHOD OF REPAIRING RUBBER BOOTS AND SHOES.

1,174,799.

Specification of Letters Patent. Patented Mar. 7, 1916.

Application filed October 19, 1914. Serial No. 867,269.

To all whom it may concern:

Be it known that I, JAMES W. ARTHUR, a citizen of the United States, residing at Warren, in the county of Trumbull and State of Ohio, have invented a new and useful Improvement in Methods of Repairing Rubber Boots and Shoes, of which the following is a full, clear, and exact description, reference being had to the accompanying drawings, forming part of this specification, in which—

Figure 1 is a view partly in side elevation and partly in vertical section and illustrating a portion of the method; Fig. 2 is a perspective view of a metal former blank employed in connection with the method; Fig. 3 is a vertical section illustrating the method as applied to the heel of a boot or shoe; and Fig. 4 is a perspective view of the shaped metal former for heel work.

My invention has relation to a novel method of repairing rubber boots and shoes, and particularly, the soles and heel portions thereof.

The object of my invention is to provide a novel, simple, inexpensive and efficient method by which a new sole or heel or partially new sole or heel can be formed on an old boot or shoe.

My invention also provides means of simple and efficient character whereby the sole or heel may be finished with a rolled edge substantially the same in appearance as that of a new boot or shoe, and also by which any desired surface configuration can be given the sole or heel, or that configuration may be replaced on rubber shoes after they have been worn smooth.

In accordance with my invention, I provide a suitably shaped sole piece 2 or heel piece 3 of the usual rubber or rubber material used in the formation of the soles and heels of rubber boots and shoes. The boot or shoe to be repaired is placed on the anvil 4 of a suitable vise 5, in which it can be clamped by means of the screw 6, carrying a suitable clamping plate 7 at its lower end. The piece 2 or 3 is placed on the sole or heel of the boot or shoe in the manner shown in Figs. 1 and 3. I next place upon the piece 2 or 3 the metal former blank of bendable metal—preferably sheet lead. The initial form of this blank for the sole of a boot or shoe is shown at 8 in Fig. 2, while the final form of the blank for heel work is shown at 9 in Fig. 4. This blank is suf-

ficiently larger than the piece to be applied to the sole or heel to leave a surrounding flange portion 10. The parts as thus assembled are then firmly clamped together by means of the screw 6, and by means of a hammer or other suitable tool, the projecting edge flanges 10 of the former blank are turned over and downwardly against the edges of the piece 2 or 3, and against the lower portion of the boot or shoe upper in the manner clearly shown in Fig. 3. The forming surface of the metal blank can be serrated or corrugated so as to impart any desired configuration therein to the bottom surface of the sole or heel and also to the rolled edges thereof.

After the former 8 or 9 has been properly shaped over the work in the manner just described, the boot or shoe is removed from the vise, and the parts are then clamped in any suitable holder and are taken to a vulcanizing apparatus and vulcanized in any usual or suitable way. The former remains in position during the vulcanizing and when removed at the completion of the vulcanizing operation, it leaves a perfectly formed sole or heel with a turned and rolled edge of neat and finished appearance substantially equal to that of a new boot or shoe.

It will be readily understood that my invention is susceptible of many modifications in the character of the apparatus employed; that the shape of the former can be changed to suit any particular job of work, and that the method is adapted to applying patches to other parts of a boot or shoe.

The method is extremely simple and can be carried out at a comparatively small expense and without very much manual skill. The metal blanks employed for the formers being made of lead or similar soft metal can be very readily and easily shaped to the work, and after being used can be readily flattened out for use again in subsequent work. The invention enables repair work to be done in a thorough and finished manner not heretofore possible.

It will also be understood that my invention may be applied to the repair and vulcanization of other rubber articles.

I claim:

1. The method of repairing the soles or heels of rubber boots or shoes, which consists in applying a vulcanizable repair piece

2
to the part to be repaired, then placing over such piece a former blank of bendable metal clamping the parts securely in place, then bending the edge portions of said blank 5 over the edge portions of the repair piece and shaping the latter, and then removing the clamping means and vulcanizing; substantially as described.

2. The herein described method of repairing rubber boots and shoes, which consists in placing a vulcanizable repair piece over the part to be repaired, then clamping a flexible former blank of lead or similar 10 easily bendable material over the repair piece, then bending or upsetting the edge portion of said blank around, and thereby shaping the repair piece to the part to be repaired, and finally vulcanizing; substantially as described.
- 20 3. In the art of vulcanizing, the method which consists in placing a vulcanizable piece over the part to which it is to be vulcanized, then clamping a solid bendable sheet metal former blank over said piece 15 with its edges projecting beyond the edges

of the repair piece, then bending the projecting edge portions of the blank over the edge portions of the repair piece, and finally vulcanizing with the former still in place; substantially as described.

4. In the art of vulcanizing, the method which consists in placing a vulcanizable piece over the part to which it is to be vulcanized, then clamping a solid bendable sheet metal former blank over said piece 35 with the edges projecting beyond the edges of the repair piece, said blank having a surface configuration, then bending the projecting edge portions of the blank over the edge portions of the repair piece, and thereby imparting the surface configuration of the blank to the repair piece, and finally vulcanizing with the former still in place; substantially as described.

In testimony whereof, I have hereunto 45 set my hand.

JAMES W. ARTHUR.
